UNITED STATES PATENT OFFICE.

RAYMOND L. TORREY, OF ATTLEBORO, MASSACHUSETTS, ASSIGNOR TO F. L. TORREY & COMPANY, OF ATTLEBORO, MASSACHUSETTS, A COPARTNERSHIP COMPOSED OF FRED L. TORREY AND JOSEPH KERKHOFF.

BELT BAND.

Application filed May 25, 1923. Serial No. 641,407.

To all whom it may concern:

Be it known that I, RAYMOND L. TORREY, a citizen of the United States, residing at Attleboro, in the county of Bristol and State 5 of Massachusetts, have invented certain new and useful Improvements in Belt Bands, of which the following is a specification.

The object of this invention is to provide a metal belt loop or band comprising a strip 10 of metal folded to provide spaced apart front and back plates and having its ends locked together by the folds of the metal and adapted to be mounted on a belt, the band being provided with a projecting eye 15 into which one end of a watch chain may be connected.

With this and other objects in view, the invention consists of certain novel features of construction, as will be more fully described, and particularly pointed out in the appended claims.

In the accompanying drawings:

Figure 1 is a view showing my improved belt band or loop as applied to a belt and to 25 which a watch chain is connected.

Figure 2 shows a strip of metal in extended position from which the band is formed.

Figure 3 is a view showing the under side 30 of my improved belt band after having been folded.

Figure 4 is a perspective view showing the band as bent nearly into finished position.

Figure 5 is an edge view showing the band as bent into finished form.

In some instances where the coat and waist-coat are removed and a belt is worn about the waist, it is found of advantage to provide some means by which the free end of the watch chain may be connected to the belt to prevent losing the watch, and to accomplish this purpose, I have formed a band of metal folded to form a band or loop to embrace the belt and which is provided with an outturned end having an eye therein to which the end of the chain may be readily attached. Further, I have formed the band of a single piece of metal which may be formed complete without the use of solder; and the following is a detailed description of one construction of such band by which the desired results may be obtained:—

With reference to the drawings, 10 design-

nates a blank from which a belt-band or 55 loop is formed, the same being preferably, constructed of sheet metal folded so as to form a front plate 11 which may be of any suitable or ornamental shape and a back plate 12 to extend around the inner face of 60 the belt and which is spaced from the front plate by means of an end plate 13, a distance approximately the thickness of the usual leather waist belt 14. One end 15 of the front plate is turned towards the back plate 65 12 and is provided with a transverse slot 16.

The opposite end of the back plate 12 is provided with a narrow tongue 17, a portion of which is turned inwardly towards the front plate, and the extremity of this 70 tongue is turned outwardly at substantially a right angle to the inturned portion to extend through a slot 16 in the opposite end member 15 and this tongue is provided near its end 18 with a hole 19 to which the end 75 of a watch chain 20 may be attached.

By this construction it will be seen that the whole band is formed of a single piece of metal and is formed completely by folding the strip constructed into the required 80 shape having one end passed through an eye in its opposite end to lock these ends together and also to provide an attaching eye to which the watch chain is attached.

By this construction, it will be seen that 85 the device is formed entirely without the use of solder which is of great advantage; first, because the same may be formed of a hard metal which may be completely bent into and permanently retain the shape into 90 which it is bent; second, by avoiding the use of solder the temper is not drawn from the stock leaving it in its original, hard condition; third, by forming the device by a single bending or folding process, the cost of 95 construction is reduced to the very minimum.

The foregoing description is directed solely towards the construction illustrated, but I desire it to be understood that I reserve 100 the privilege of resorting to all the mechanical changes to which the device is susceptible, the invention being defined and limited only by the terms of the appended claims.

I claim:

1. A belt band for watch chains formed by folding a strip of metal upon itself to form spaced-apart front and back plates,

one end being slotted and turned inwardly and the opposite end being provided with a narrow tongue extending through said slot and having an eye into which a watch chain ⁵ may be connected.

2. A belt band for watch chains formed by folding a single strip of metal upon itself to have spaced apart front and back plates the opposite end portions being turned to

extend inwardly toward each other, one end portion being slotted and the extremity of the other being folded to have a right angled projecting portion to extend outwardly through said slot and having an eye to which a watch chain may be connected. ¹⁰

In testimony whereof I affix my signature. ¹⁵

RAYMOND L. TORREY.
